(57) **CLAIM**

The ornamental design for a display rack, as shown and described.

DESCRIPTION

FIG. 1 is a perspective view of the display rack of the present invention;

FIG. 2 is a front elevation view of the display rack of the present invention, with the rear elevation view a mirror image of the front elevation view;

FIG. 3 is a right elevation view of the display rack of the present invention, with the left elevation view a mirror image of the right elevation view;

FIG. 4 is a top plan view of the display rack of the present invention; and,

FIG. 5 is a bottom plan view of the display rack of the present invention.

The broken lines showing a representation of a base and ornamental balls of the display rack, as shown in all Figures, are for illustrative purposes only and form no part of the claimed design.
